ELECTRIC APPARATUS

Filed Sept. 23, 1925.

Fig. 2

Inventor:
William E. Paul,
by Alexander S. Smith
His Attorney.

UNITED STATES PATENT OFFICE.

WILLIAM E. PAUL, OF SCHENECTADY, NEW YORK, ASSIGNOR TO GENERAL ELECTRIC COMPANY, A CORPORATION OF NEW YORK.

ELECTRIC APPARATUS.

Application filed September 23, 1925. Serial No. 58,156.

My invention relates to electric apparatus of the kind which includes an enclosing casing through the top of which extend conductors supported in insulator bushings. It is an object of my invention to provide apparatus of this character having improved means for dissipating the heat generated in the conductor by the current carried thereby.

My invention will be better understood from the following description taken in connection with the accompanying drawing, and its scope will be pointed out in the appended claims.

Referring to the drawing, Fig. 1 is a side elevation with parts shown in section of an electric switch embodying my invention; and Fig. 2 is a cross section taken on line 2—2 of Fig. 1.

On the drawing I have shown at 1 the tank of an oil switch through the cover 2 of which extends the insulator bushings 3 and the operating rod 4 carrying the bridge 5. The bushings are shown mounted in the cover in the customary manner by being cemented in the ring 6 which is bolted to the cover. In switches of this type as ordinarily constructed the terminal studs which pass through the insulator bushings and by which the circuit connections are made with the stationary contacts of the switch are solid. Under conditions of heavy load excessive heating of the studs sometimes occurs, particularly in their central portions where being surrounded by the bushing the loss of heat is the least. In accordance with my invention I have made the stud 8 hollow and have made provision for the passage of a ventilating current into and out of the stud. In the lower end of the hollow stud 8 is secured the stationary contact 9 and at the upper end is secured the lead 10 by means of suitable clamping nuts 11 in the usual and well known manner. The contact 9 closes the lower end of the hollow stud and within the stud is the tube 12 which preferably is of insulating material and of such a diameter that the passages within and without the tube have approximately the same cross sectional area. The tube 12 is shown resting upon the contact 9 and provided with cut away portions 13 forming passages between the interior and the exterior

of the tube. Near the top of the tube is shown a deflecting ring 14.

Due to the heating of the air between the tube and the walls of the stud a natural draft of air is produced, the warm air outside of the tube arising while cooler air flows down through the tube to replace it. Under certain circumstances it may be desirable to have a forced circulation of air or other cooling medium in which case suitable means may be employed to induce the desired circulation.

While I have chosen to illustrate my invention as applied to an oil switch it is not limited to such but is applicable to various other electrical apparatus having enclosing casings such for example as transformers.

What I claim as new and desire to secure by Letters Patent of the United States, is:

1. In electric apparatus having an enclosing casing, an insulator bushing in the top thereof, a hollow terminal stud in the bushing, and a member extending longitudinally in the stud dividing the opening therein into an inner and an outer passageway, said passageways being in communication with each other at their lower ends and being open to the atmosphere at their upper ends.

2. In electric apparatus having an enclosing casing, an insulator bushing in the top thereof, a hollow terminal stud in the bushing, and a longitudinally extending tube in the stud spaced from the walls thereof to form inner and outer passages which connect with each other at their lower ends and which are open to the atmosphere at their upper ends whereby cooling air may enter the stud through the tube and escape between the tube and the walls of the stud.

3. Electric apparatus comprising current carrying members immersed in insulating liquid, an enclosing casing therefor, an insulator bushing extending through the top of the casing, a hollow terminal stud in said bushing secured at its lower end to one of said members and open at its upper end, a tube open at its upper end extending down into said hollow stud and means for spacing the tube at its sides and lower end from the stud whereby the stud is cooled by a natural circulation of air over its inner surface.

4. An electric switch comprising relatively

movable contacts separable in an insulating liquid, an enclosing vessel therefor, an insulator bushing extending through the top of the vessel, a hollow terminal stud in said bushing secured at its lower end to one of said contacts and open at its upper end, a tube open at its upper end extending down into

said hollow stud, means for spacing the tube at its sides and lower end from the stud and a deflector on the tube above the upper end of 10 the stud.

In witness whereof, I have hereunto set my hand this 22nd day of September, 1925.

WILLIAM E. PAUL.
